(57) **CLAIM**

I claim the ornamental design for a semi-con shaving tool with reverse drive, as shown and described.

DESCRIPTION

FIG. 1 is a front left top perspective view of a semi-con shaving tool with reverse drive design according to my invention;

FIG. 2 is a front left bottom perspective view of the semi-con shaving tool with reverse drive design shown in FIG. 1;

FIG. 3 is a front right bottom perspective view of the semi-con shaving tool with reverse drive shown in FIG. 1;

FIG. 4 is a front right top perspective view of the semi-con shaving tool with reverse drive shown in FIG. 1;

FIG. 5 is a front elevational view of the semi-con shaving tool with reverse drive shown in FIG. 1;

FIG. 6 is a back elevational view of the semi-con shaving tool with reverse drive shown in FIG. 1;

FIG. 7 is a top elevational view of the semi-con shaving tool with reverse drive shown in FIG. 1;

FIG. 8 is a left elevational view of the semi-con shaving tool with reverse drive shown in FIG. 1;

FIG. 9 is a right elevational view of the semi-con shaving tool with reverse drive shown in FIG. 1; and,

FIG. 10. is a bottom elevational view of the semi-con shaving tool with reverse drive shown in FIG. 1.
